(57) **CLAIM**

The ornamental design for a toothbrush with floss dispenser, as shown and described.

DESCRIPTION

FIG. 1 is a front perspective view of a toothbrush with floss dispenser;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The evenly-incremented broken lines illustrate portions of the toothbrush with floss dispenser that form no part of the claim. The dot-dash broken line illustrates a boundary, and forms no part of the claimed design.

1 Claim, 5 Drawing Sheets(56)
